CLAIM

I claim the ornamental design for a rearview mirror assembly with passenger monitoring, as shown and described.

DESCRIPTION

FIG. 1 is a front perspective view of a rearview mirror assembly with passenger monitoring of the present disclosure;

FIG. 2 is a side front perspective view of the rearview mirror assembly of FIG. 1;

FIG. 3 is a bottom front perspective view of the rearview mirror assembly of FIG. 1;

FIG. 4 is a bottom perspective view of the rearview mirror assembly of FIG. 1;

FIG. 5 is a bottom rear perspective view of the rearview mirror assembly of FIG. 1;

FIG. 6 is a front elevational view of the rearview mirror assembly of FIG. 1;

FIG. 7 is a rear elevational view of the rearview mirror assembly of FIG. 1;

FIG. 8 is a first side elevational view of the rearview mirror assembly of FIG. 1;

FIG. 9 is a second side elevational view of the rearview mirror assembly of FIG. 1;

FIG. 10 is a bottom plan view of the rearview mirror assembly of FIG. 1;

FIG. 11 is a front perspective view of a rearview mirror assembly with passenger monitoring of the present disclosure;

FIG. 12 is a side front perspective view of the rearview mirror assembly of FIG. 11;

FIG. 13 is a bottom front perspective view of the rearview mirror assembly of FIG. 11;

FIG. 14 is a bottom perspective view of the rearview mirror assembly of FIG. 11;

FIG. 15 is a bottom rear perspective view of the rearview mirror assembly of FIG. 11;

FIG. 16 is a front elevational view of the rearview mirror assembly of FIG. 11;

FIG. 17 is a rear elevational view of the rearview mirror assembly of FIG. 11;

FIG. 18 is a first side elevational view of the rearview mirror assembly of FIG. 11;

FIG. 19 is a second side elevational view of the rearview mirror assembly of FIG. 11; and,

FIG. 20 is a bottom plan view of the rearview mirror assembly of FIG. 11.

Broken lines are environmental only and form no part of the claimed design.
